UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,153,047.

Specification of Letters Patent.

Patented Sept. 7, 1915.

Application filed April 4, 1912. Serial No. 688,569.

To all whom it may concern:

Be it known that I, FRANK DUTCHER, a citizen of the United States, residing at Versailles, in the county of Allegheny and State 5 of Pennsylvania, have invented certain new and useful Improvements in Railway Signal-Torpedoes, of which the following is a specification, reference being had therein to the accompanying drawing.

10 My invention relates to improvements in railway signal torpedoes, and it pertains to a torpedo made up of a thin paper explosive case covered with a thin metallic foil.

15 In railway signal torpedoes which use paper explosive containing cases heretofore known to me, it has been necessary to make these cases thick in order to be able to make the paper case waterproof. These thick paper cases form an objectionable cushion 20 sometimes preventing explosion.

25 One object of my present invention is to provide a thin metallic foil covering for a paper case torpedo, whereby the paper case can be made of thin paper overcoming the cushion effect, the metallic foil providing an efficient waterproof protection for the case and the explosive therein and at the same time so thin that there will be no appreciable flying metal particles when the torpedo 30 explodes.

35 Another object of my present invention is to so apply the foil metallic covering to the paper case that a metal strap carrying clip can be clamped to the cover without engaging the paper case, whereby all danger of explosion in clamping the clip to the torpedo in process of manufacture is prevented.

40 Another object of my present invention is to make this metallic foil of aluminum whereby it is sufficiently tough and strong not to be cut or injured by the clamping edge of the clip under the clamping pressure and to stand the use of handling and application to the railway rail without being 45 injured.

50 In the accompanying drawings—Figure 1 is a perspective view of my improved torpedo showing it carrying two lead straps and in position on a railway rail. Fig. 2 is a sectional view on the line 2—2 of Fig. 1. Fig. 3 is a sectional view on the line 3—3 of Fig. 2. Fig. 4 is a perspective of the parts of the torpedo shown in separated relation. Fig. 5 is an inverted view of the torpedo, 55 showing a clip constructed to receive a

spring strap. Fig. 6 is a side elevation, showing the spring strap torpedo on the railway rail and spring strap broken and falling away in dotted lines. Fig. 7 is a side view of a clip with two lead straps applied thereto and in position on a railway rail. Fig. 8 is a sectional view on the line 8—8 of Fig. 7. Fig. 9 is an inverted perspective view of the clip constructed to receive either two lead straps or a spring strap. 60

Referring now to the drawings in which like reference characters denote the same parts, 1 is an open ended thin paper case to receive an explosive compound 2. This compound is preferably held in the case by a 70 suitable composition 3, placed in and sealing the open ends of the case 1. Placed around this case 1 and entirely inclosing it is a thin metallic foil 4, preferably made of aluminum. This foil covering 4 is made in the 75 form of a blank, as shown in Fig. 4. The paper case, as here shown, is preferably made of a double wedge-shape at its edges, as clearly shown in Figs. 1, 3 and 4. The foil covering is made from a sheet 5, preferably formed, as shown in Fig. 4, and preferably has its longitudinal edges cut away at its ends 6 and at its central portion 7, and is adapted to be folded on the dotted lines *a* to have the ends *b* extend under the bottom 80 of the case 1, and double folded on the diagonal lines *c* to fold under the corners of the case and bent downward at the lines *d* to fit the wedge-shaped top of the torpedo, and outward at the lines *e* to form the outwardly 85 extending top flanges *f*, the edges of the portion 6 forming the under portion *g* of said flanges. The overlapping portions of the metallic foil covering are cemented with a suitable waterproof cement and flanges *f* 90 and *g* project beyond the sides of the case, as shown, and constitute flanges around which the edges *h* of the strap carrying clamp 8 are folded and clamped, as shown clearly in Figs. 2 and 3. The corners 9 of 100 the foil sheet are so folded that the sheet is at an angle, as shown at the point 10, (Fig. 1) so that the foil does not extend to the extreme corners of the turned end flanges *h*. This enables the corners *i* of the flanges 105 to be bent in contact and to form shoulders by reason of this construction, which prevent the clip from possibly being slid end-wise off of the torpedo.

110 It is understood, of course, that the flanges

h are to be tightly clamped on the flanges *f*, *g*, but this bending of the corners, as stated, adds additional security against any movement whatever of the clip on the torpedo.

- 5 If desired, the completed torpedo may be dipped into a waterproof compound. It has been found in practice, difficult to make a paper explosive containing case sufficiently waterproof to stand the severe tests required 10 by railroads in order to meet the conditions required in excluding moisture under all weather conditions to which railway signal torpedoes are subjected, and it has been found that to meet these requirements it is 15 necessary to make the paper cases thick, and to do this from six to eight layers or wrappings of paper is required. The thick wall case thus formed provides an objectionable cushion which, in practice, sometimes prevents the explosion of the compound within 20 the case when the wheel of the locomotive passes thereover. This will be appreciated when it is understood that for safety in the manufacture and handling of the torpedo it 25 is not practical to have a very sensitive explosive compound.

My improved torpedo, as herein described, overcomes the foregoing difficulties and makes an efficient and reliable torpedo. It 30 enables a thin paper case, from two to three layers, to be used which avoids the cushion effect, before referred to, while at the same time the metallic foil covering enables an efficient waterproofing of the torpedo to exclude the moisture and to meet all 35 the tests required without the before mentioned objections.

In Fig. 4 the metal clip 8, is provided 40 with openings 11, through which a spring clip 12, such as shown in Fig. 5 may be applied thereto, and also openings 13, through which two lead straps 14 may be passed, whereby the clip enables the manufacturer 45 to use either a spring strap or lead straps. This does not form any part of my present invention, but is made the subject-matter of the claims of a co-pending application, and, for this reason, no claim is made in this application therefor.

50 In Figs. 5 and 6, I show the clip 8, with only the openings 11 for the spring strip 12. The bends 15 in the spring strip are for caus-

ing the strip to break when passed over by the wheels of a car and fall away, as shown in Fig. 6. This forms no part of my present 55 invention and no claim is herein made therefor, since it is the subject-matter of claims of a co-pending application.

Figs. 7 and 8 show views of my improved 60 torpedo in which the clip 8' has the openings 11, and has the strap openings 16 differently positioned from the strap openings 13 of Fig. 4.

Having thus described my invention, what I claim and desire to secure by Letters Patent is:

1. An improved railway signal torpedo, comprising a thin paper explosive containing case and a cover of thin metallic foil enclosing the said explosive containing case and projecting beyond the ends of the said explosive containing case and formed into projecting clip receiving flanges, a clip having its end turned over to form flanges, a rail-engaging strap carried by the said clip, 75 the said flanges of the said clip clamping the said projecting clip receiving flanges, whereby all danger of explosion in clamping the clip to the torpedo is prevented and whereby a water-proof non-flying torpedo is 80 produced in which cushioning by the impact of the car wheels is prevented.

2. A railway signal torpedo comprising a thin paper explosive containing case, a cover of metallic foil folded about the said case, 85 the junction of the said folds projecting beyond the ends of the said case, the corners of the said folded ends folded upon themselves, and a clip having its ends turned over to form flanges, the said flanges of the clip 90 clamping the said projecting ends of the folds and the folded corners thereof forming means for attaching the clip to the foil covering without engaging the explosive containing case, the folded corners of the metallic covering forming means for locking the clip to the said covering.

In testimony whereof I hereunto affix my signature in the presence of two witnesses.

FRANK DUTCHER.
